UNITED STATES PATENT OFFICE

CLARENCE G. CARLSON, OF CHICAGO, ILLINOIS, ASSIGNOR TO CHICAGO CURTAIN STRETCHER COMPANY, OF CHICAGO, ILLINOIS, A CORPORATION OF ILLINOIS

CURTAIN STRETCHER

Application filed December 17, 1928. Serial No. 326,551.

This invention relates to curtain stretchers and particularly to folding stretchers wherein two sections of a side or end member are hinged together so that they may be folded 5 for convenient disposition when the stretcher is not in use.

The invention comprises certain improvements on the stretcher covered by Letters Patent No. 991,781 patented May 9, 1911.

10 The object of the invention is to lock the hinge and the sections of the member together rigidly and securely for maintaining the stretcher sections in aligned position and prevent the member from yielding or breaking 15 joint at the hinge.

A further object of the invention is to provide a novel locking device for cooperation 20 with the hinge at the joint between the abutting ends of the sections for securing the hinge and the sections rigidly together in open position.

In the accompanying drawings illustrating a selected embodiment of the invention

Fig. 1 is a top plan view of the hinged ends 25 of two side member sections of the stretcher in open position;

Fig. 2 is a bottom plan view of the part shown in Fig. 1;

Fig. 3 is a view similar to Fig. 1 but showing the hinged joint partly open; and

Fig. 4 is a sectional view on the line 4—4 of Fig. 1.

Referring to the drawings 5 represents one of the side members of a curtain stretcher 35 frame and comprising the sections 6 and 7 which are connected together by a hinged joint. The hinge comprises the two hinge plates 8 and 9 which are pivoted together at 10 and are applied to the bottom of the 40 sections, being provided with edge flanges 11 to engage the edges of the sections. Prongs or projections 12 are struck up from the hinge plates and are driven in to the sections to assist in securing the hinge plates rigidly 45 to the sections. A plate 13 is arranged on the top of the section 6 and this plate and the hinge plate 8 are secured to the section by the rivet 14. A plate 15 is arranged on top of the section 7 and this plate and the 50 hinge plate 9 are secured to the section by

the rivet 16. The plate 15 is bent at 17 and at 18 to provide a crowned yielding locking portion having a downward projecting shoulder 19 and an upturned end 20. The plate 13 has an up-bent shoulder 21 and a downwardly extending end 22. The shoulder 19 is arranged to ride over the shoulder 21 when the hinge is closed and the sections are aligned, Fig. 1, and then the shouldered end portion of the plate 13 lies under the crowned portion between the shoulders 17—18 of the plate 15, and the shouldered end portion 19 of the plate 15 lies above the plate 13 behind the shoulder 21. A bolt 23 passes through the plate 15, between the abutting ends of the sections through a slot 8' in the plate 8 and through an opening in the plate 9, and carries a wing nut 24. The end of the section 7 is provided with a groove 7' to accommodate the bolt 23 and the end of the section 6 also has a groove 6' which registers with the groove 8' in the plate 8 and with a groove 13' in the free end of the plate 13 to accommodate the bolt which is centered, when the hinge is closed, in the joint between the ends of the sections.

In practice the stretcher is usually folded for storage and the wing nut is loosened on the bolt. In closing the hinge the shoulder 19 rides over the shoulder 21 to the position shown in Fig. 4 with the sections 6—7 aligned and their ends abutting. Then the wing nut is tightened and the overlapping portions of the hinge plates are clamped together and upon the joint of the sections and the yielding shouldered end portion of the plate 15 is clamped tightly upon the shouldered end portion of the plate 13 thereby locking the parts together with the sections rigid in alignment. The shoulders on the plates 13, 15 provide an interlocking engagement which is maintained by the bolt and nut 23—24 which also clamp the spring plates together and upon the sections whereby a rigid joint is obtained and maintained throughout the use of the stretcher. The crowned portion of the plate 15 is yielding so that the shoulder 19 will ride over the shoulder 21 in closing and in opening the hinge. The invention provides a novel and simple means for join-

UNITED STATES PATENT OFFICE

VINCENT D. CARROLL, OF CHICAGO, ILLINOIS

COFFEE URN

Application filed January 11, 1926. Serial No. 80,401.

My invention relates to coffee urns.

It relates more particularly to temperature controlling devices for the types of coffee urns commonly used in lunch rooms, restaurants, etc.

In the use of coffee urns prior to my invention, the supply of gas or other fluid fuel to the burner has been manually regulated. Due to the carelessness or forgetfulness of those having charge of making the coffee, the coffee frequently was not heated to the proper temperature or the burner was at times unnecessarily left burning at full pressure, resulting in a waste of gas and occasionally in the burning out of the bottom of the urn.

It is an object of my invention to provide a simple and effective means for automatically controlling the temperature of the coffee.

A further object is to provide means by which a coffee urn may be readily adapted to be equipped with my regulating device.

A further object is to provide a fuel saving device for coffee urns.

A further object is to provide a simple safety device for preventing excessive differences of pressure between the atmosphere and the inside of the water container of the urn and for indicating when the water level in the container is low.

Other objects will appear from the following specification, and reference being made to the accompanying drawings, in which,

Figure 1 is an elevation of a water heater and a coffee urn, the latter being shown partly in section.

Figure 2 is a section of the regulator taken on line 2—2 of Fig. 1.

Figure 3 is a section of the by-pass valve taken on line 3—3 of Fig. 1.

Figure 4 is an enlarged plan view of a portion of the sealing ring.

Figure 5 is an enlarged sectional view thereof, taken on the line 5—5 of Fig. 4.

A water heater 6, shown in outline form in Figure 1, is ordinarily used to supply hot water to one or more coffee urns 7, being connected thereto by a pipe 8 in which the flow is regulated by a valve 9. The coffee urn comprises a container 10 mounted on legs 11, and having a removable cover 12. A coffee jar 13,

usually made of vitrified china, is supported in the container by means of the draught pipe 14 which passes through the side of the container, and its outer end is equipped with a faucet 15. The coffee bag 16 is suitably supported in the top of the coffee jar 13. A flanged ring 17 resting upon the top edge of the coffee jar causes the supply water from the pipe 8 and the condensation from the top of the container to drain into the jar. The space between the jar and the container is partly filled with water which is heated by a burner 18, which is represented as a gas burner supplied with gas by the pipe 19.

The supply of gas to this burner, as will be hereinafter described, is regulated by pressure generated in the space surrounding the coffee jar. It is therefore necessary to seal this space from the atmosphere. I accomplish this by means of an annular rubber tube 20 which fits between the outer surface of the jar 13 at its upper edge, and the inner surface of the container. After the tube is in place it is compressed to form a tighter seal by tightening the closely spaced screws 21 which pass freely through the semi-cylindrical washers 22, diametrically through the tube 20, and are threaded in the nuts 23 which are similar to the washers in shape. The washers 22 have pin-like projections 22^a which are formed by an incomplete punching operation. The washers 22 are connected by links 24 which have elongated slots 24^a fitting over the projections 22^a. The provision of these slots permits the tube to be cut to a standard length and to be stretched to fit slightly varying sized containers.

It will be obvious that by tightening the screws 21, the tube will be laterally deformed to form a seal between the jar and the container which will be sufficiently tight to hold the small pressures which I use in my regulating device. A small tube 25 extends into the water in the container some distance below the normal water line. The tube is held and sealed in place in the usual filling pocket 13^a by a packing 26, preferably of lead wool soaked in red lead, or some other suitable binding material. It has been found that this method of packing is very satisfactory, since
